UNITED STATES PATENT OFFICE

2,361,486

FLASHING INCANDESCENT LAMP

William F. MacGregor, Toronto, Ontario, Canada,
assignor to General Electric Company, a corporation of New York

Application January 26, 1944, Serial No. 519,766
In Canada August 18, 1943

4 Claims. (Cl. 315—32)

This invention relates to electric incandescent lamps and particularly to flashing lamps where the filament is automatically energized intermittently.

It has been previously proposed to construct an incandescent filament lamp with a bi-metal element adjacent the filament and arranged in the circuit to the filament in such a manner that when the lamp is cold the circuit is complete and filament is energized but when the filament heats up the bi-metal element bends to break the circuit and deenergize the filament, the sequence of operations being continued automatically. Such lamps are desirable for signalling purposes on account of the conspicuousness of a flashing lamp and particularly because of the longer battery and lamp life obtained for a given overall period of operation.

My invention relates to constructional features of a lamp as above described whereby a rugged mounting of the parts is obtained to withstand the vibration and shocks encountered in use and whereby cheapness of manufacture and reliability of operation are also obtained.

For a complete understanding of my invention, reference is had to the following detailed description of an embodiment of my invention in which Fig. 1 is a perspective view with the base shown partly in section; and Fig. 2 is a view from a position approximately at right angles to Fig. 1 but with the base omitted and the bulb shown fragmentarily.

The lamp shown in the drawing comprises a bulb 18 with a neck 11 having a butt seal 12. The butt seal is formed by fusing to the end of the neck of the bulb, the end of a tube of the same diameter which tube is used as an exhaust tube, and sealing in the lead wires for the lamp filament at the point of fusion. The butt seal is known in the art in small size lamps and is well adapted for cheap manufacture on a machine such as shown in Patent 1,742,153, Stiles et al., dated December 31, 1929.

The mount comprises three support wires 14, 15 and 16 fused through a glass bead 17 with the wires equally spaced from one another, that is arranged in the bead at the three corners of an equilateral triangle. The upper end of the support wire 14 is bent just above the bead 17 to extend at right angles to itself as indicated at 18. The support wire 15 extends above the bead 17 a greater extent than the wire 14 and has its end bent as indicated at 19 to be parallel to the bent end 18. The support wire 16 extends above the bead 17 to a point intermediate the bent ends

5 of 18 and 19, and has a refractory metal filament 20 welded to the end thereof and also to the support wire 15 midway of its length above the bead. A strip 21 of bi-metal has one end welded to the end 18 in such a manner that, under normal temperature conditions with the filament 20 cold, it bears against the bent end 19 completing an electrical circuit at this point. As shown in the drawings the filament 20 extends transversely of the bi-metal strip about the middle portion thereof and spaced in close proximity thereto. The bi-metal 21 is so arranged that when it is warmed up by the heating of the filament it bends away from the end 19. The mount as above described is a compact arrangement of parts which is readily manufactured and its overall transverse dimensions are such that it will pass easily through the neck 11 of the bulb. The ends of the support wires 10 14, 15 and 16 below the bead extend through the seal 12 at the lower end of the neck 11, are spaced 120 degrees apart therein, and are fused therein at the time the seal is made. The mount with the triangular arrangement of the support wires 15 extending from the seal forms a strong support for the parts not easily damaged by shocks.

20 To the neck of the bulb is applied a two contact snell. This is shown as of the known screw-shell type with the extension of the support wire 20 14 outside the seal soldered to the shell 22 and with the extension of the support wire 16 outside the seal soldered to the center contact 23. The support wire 15 is supported in the seal but has no external electrical connection.

25 The operation of the lamp will be apparent from the above description. When the electrical circuit leading to the contacts 22 and 23 is closed the circuit through the lamp is completed from contact 23 through support wire 14, bi-metal strip 21, arm 19, support wire 15, filament 20 and support wire 16 to the shell contact 22. The filament lights up and the heat therefrom causes the bi-metal to bend and break contact with the arm 19 thereby breaking the circuit. When the filament 30 cools down the bi-metal also cools after a time lag and again completes the above described circuit at the arm 19. The filament is thus lighted intermittently as long as the external circuit remains closed.

35 The lamp described is of a sturdy construction, reliable in operation and adapted to low cost manufacture. While I have described in detail a specific form of my invention, I do not desire to 40 be limited thereto but to include all modifications

which fall within the scope of the appended claims.

What I claim as new and desire to secure by Letters Patent of the United States is:

1. A flashing incandescent lamp having a glass bulb with a neck, a mount comprising three spaced support wires fused in a glass bead, a lamp filament arranged between a pair of the support wires and lying substantially transverse to the length thereof, a bi-metal strip arranged between another pair of said wires and lying substantially lengthwise thereof and with its middle portion closely adjacent to the filament, the support wires below the bead extending through the neck and sealed in circumferentially spaced relation in a butt seal at the end thereof.

2. A device of the class described comprising a bulb having a neck portion and butt sealed at the end of the neck, three support wires fused in the seal in spaced relation about the neck and extending into the bulb, an insulating bead fused to the wires at a point above the seal holding them in spaced parallel relation, the first of said support wires terminating a short distance above the bead, the second of said support wires projecting substantially above the upper end of the first support wire, a strip of bi-metal having one end welded to the end of said first wire in such a manner that it makes contact with the end of the second wire and bends out of contact therewith when heated, the third support wire projecting above the bead to a point intermediate the ends of said first and second wires, a lamp filament welded to the end of the third wire and to an intermediate point on the second wire and lying transverse to and spaced close to an intermediate point of the bi-metal, the ends of the first and third wires projecting outside the seal and connected to circuit making contact.

3. A device of the class described comprising a

5 glass bulb having a neck portion and butt sealed at the end of the neck, three support wires fused in the seal at equally spaced points circumferentially thereof and extending into the bulb, a glass bead fused to the wires at a point spaced from the seal and holding them in spaced parallel relation, the first of said support wires terminating a short distance beyond the bead and having its end bent substantially parallel to the bead, the second of said support wires extending substantially farther into the bulb and having a bent end lying parallel to and spaced from the bent end of the first wire, a strip of bi-metal having one end welded to the bent end of said first wire 10 in such a manner that its other end is in contact with the bent end of said second wire when cold and bends out of contact therewith when heated, the third of said support wires extending beyond the bead, and a lamp filament extending between 15 said second and third support wires and lying adjacent the bi-metal, the ends of the first and third support wires outside the seal being connected to circuit making contacts.

4. A flashing incandescent lamp comprising a sealed bulb, three spaced support wires extending into the bulb in the same direction and terminating at different levels spaced apart substantial distances, the intermediate wire terminating at a point approximately midway between the shorter and longer wires, a bi-metallic strip extending longitudinally between the ends of the shorter and longer wires, said strip being secured to the end of the shorter wire and engaging the end of the longer wire when it is cold, a filament extending laterally between and electrically connected to the end of the intermediate wire and a point on the longer wire, and a pair of external contacts connected respectively to the said shorter and intermediate wires.

WILLIAM F. MACGREGOR.
